BIRD FEEDER

Donald B. Hyde, Newtonville, Mass.; Joyce P. Hyde, executrix of said Donald B. Hyde, deceased

Application July 10, 1953, Serial No. 25,876

Term of patent 14 years

(Cl. D31—2)

To all whom it may concern:

Be it known that I, Donald B. Hyde, a citizen of the United States of America, residing at Newtonville, Middlesex County, Massachusetts, have invented a new, original, and ornamental Design for Bird Feeder, of which the following is a specification, reference being had to the accompanying drawing, forming a part thereof, in which the figure is a view in perspective of a bird feeder, showing my new design, views from the opposite sides being substantially the same as the view shown.

I claim:

The ornamental design for a bird feeder, substantially as shown and described.
